FOUNDRY CUPOLA

Robert André Marcel Ronceray, Thiais, France

Application October 25, 1950, Serial No. 191,955

Claims priority, application France
September 25, 1950

2 Claims. (Cl. 266—30)

1

In the course of a melting operation in a cupola, the lining of the latter melts and its melted particles drip down, along the cupola walls, until they reach the tuyère level where, by being air-cooled, they are solidified, giving rise to deposits more or less obstructing the tuyères.

Most cupolas have hitherto been constructed with their tuyères located in the same plane as the air box and arranged to operate continuously, all at the same time. On account of this construction, the tuyères are always partly obstructed, the air supply being subject to variations in the course of one and the same melting operation, whereby serious disturbances in the melting process are caused, resulting in deficient melted products, irregular melting rate per hour and variations of the pouring temperature.

On the other hand, since the tuyères are located in the same plane as the air box, the air pressure is not equal in all of them and is, in fact, higher in the tuyères lying in proximity to the air admitting duct than the tuyères diametrically opposed to these ducts. Every tuyère, therefore, discharges a different amount of air, so that in the cupola there occur regions in which the melting is not being carried out under desirable conditions.

There have been constructed cupolas provided with two sets of tuyères arranged to operate alternately. In this case, the tuyères not in use are brought to so high a temperature as to cause the deposits on the tuyères to melt away. But as the permutation of the sets of tuyères is controlled by hand and is often left to the decision of the furnaceman, a satisfactory operation is not always absolutely ensured, this shortcoming being aggravated by the inequality of the air pressure in the tuyères.

There have further been constructed cupolas in which the air box is located at a level higher than that of the tuyères and is connected to the latter by vertical ducts. The distribution of air is better in these cupolas, but important losses of head take place in the connecting ducts.

The present invention has for its object to provide improvements in the foundry cupolas, which permit of obtaining the automatic removal of tuyère deposits, the equality of air pressure in the tuyères, with reduced losses of head, a smaller wear of the cupola facing, and a heating of the air employed.

According to a first improvement, the cupola is provided with two independent sets of tuyères, and includes self-acting means whereby each set of tuyères may be set in action alternately.

2

The cleaning of the tuyères is then effected regularly and entirely automatically. The air supply is uniform and hence the quality of melted products is regular.

5 The air supply of each group of tuyères can be timed by the head melter and the crews therefore do not have to intervene whereby their fatigue is minimized and the operation of the cupola is even and regular at all times.

10 Preferably, the various tuyères are converging and equally spaced circumferentially of the cupola. This disposition increases the effectiveness of the automatic cleaning of the tuyères; also, it prevents the jet of air from being dispersed, and the air blown in by one set of tuyères does not cool the tuyères of the other set being cleaned.

15 According to a further improvement, which may be used jointly with the first one or independently, the air box is located at a level different from that of the tuyères and is connected to the latter by a subdivided jacket surrounding the cupola. In this way, the air pressure is practically equal in all of the tuyères and the losses of head are rendered low by the large dimensions given to the connecting ducts. On the other hand, the air that circulates within the jacket, throughout the height of the melting region, is warmed up by cooling this region as well as the lining of the latter. Wear of this lining is thereby substantially reduced, for the temperature of the same is about equal to its melting point, when the cupola is in operation.

20 25 30 35 40 An example of execution of the improved foundry cupola, designed according to the present invention, will now be described with reference to the accompanying more or less diagrammatic drawings, it being understood that the outstanding features apparent from both the drawings and the following description form part of this invention.

In the drawings:

Fig. 1 is a vertical showing of the cupola, half in elevation and half in section;

Fig. 2 is a cross-section through the line II—II of Fig. 1;

Fig. 3 is a cross-section through the line III—III of Fig. 1; and

Fig. 4 is a detail view showing the distribution 45 50 55 shutter.

Referring to the drawings, it will be seen that the cupola 1, whose lining is denoted by reference 2, is provided with an air box 3 connected to the air supply duct 4 and divided into two portions by a transversal partition 5. A shutter 6,

provided with an aperture 6a, is placed across the duct 4 and adapted, when being displaced, to set this duct in communication with one or the other portions of the box 3. The shutter 6 is connected to a piston 7 slideable in a double-acting cylinder 8. Compressed air may be sent into one or the other cylinder end through the intermediary of a valve 9 actuated by an adjustable clockwork 10.

A jacket 11, made of welded sheet metal, surrounds the cupola below the air box 3 and is provided with partitions such as 12 adapted to define compartments such as 13. One of every two of these compartments communicates with the upper portion of the air box through apertures such as 14 formed in the partition 5, while the other compartments communicate with the lower portion of this box through apertures such as 15 formed in the bottom of said box.

At their lower ends the compartments 13 communicate with radially extending tuyères such as 16 equally spaced circumferentially of the cupola and each of which tuyère has a converging longitudinal cross section with the small end thereof opening on the inner wall of said cupola. Inspection doors such as 17 are positioned in front of the tuyères 16.

The clockwork 10 is for setting in operation alternately the tuyères 16 in communication with the upper portion of the air box 3 and the tuyères in communication with the lower portion of this box. The tuyères which are thus caused to be out of action are brought to high temperature and their deposits melt away. The air flowing into the jacket 11 is heated and its pressure is practically equal in all of the tuyères in action.

The outlet 18 of the cupola opens into a decanting vat 19. The iron slag which is lighter than iron rises to the surface and flows therefrom through an upper passage 20, while the iron collects in the bottom of the vat 19 and is withdrawn through a lower passage 21.

The melted products obtained with such a cupola are of better quality than those obtained with the cupolas hitherto known, since the pouring temperature of the former is more regular. The output of these products varies within narrow limits. The melter does not have to busy himself about the cleanliness of the tuyères, and his inspection work is reduced. The air blast is heated, and the condition of the lining is improved, especially where this is most exposed.

What I claim is:

1. An improvement in foundry cupolas comprising a cupola, an airbox surrounding the middle portion of said cupola, a partition extending transversely of and within said airbox and separating said box into two sections positioned one above the other, an air inlet duct connected to said airbox and in communication with both of said sections, a shutter slidably mounted between

5 said duct and said airbox and having an opening capable of placing said duct in communication with one of said airbox sections at a time according to the position of said shutter, a pneumatic jack connected to said shutter for operating the same, a clockwork mechanism operably connected to said jack for automatically operating same, a plurality of tuyères provided through said cupola all on the same horizontal plane below said air box, a plurality of vertical conduits connecting alternate tuyères to one of said airbox sections, and a second plurality of vertical conduits connecting the remaining tuyères to the other of said airbox sections.

2. An improvement in foundry cupolas comprising a cupola, an airbox surrounding an upper portion of said cupola, a partition extending transversely of and within said airbox and separating said airbox into two sections positioned one above the other, an air inlet duct connected to said airbox and in communication with both of said sections, a shutter slidably mounted between said duct and said airbox and having an opening for placing said duct in communication with one of said airbox sections at a time according to the position of said shutter, a pneumatic jack connected to said shutter for operating the same, a clockwork mechanism operably connected to said jack for automatically operating same, a plurality of tuyères provided through said cupola all on the same horizontal plane below said airbox, a jacket enclosing the portion of said cupola extending from said airbox to and below said tuyères, said airbox having an annular opening provided in the bottom thereof, said transverse partition having an annular series of openings provided therethrough, a plurality of partitions extending vertically of and radially across said jacket and through said airbox opening and the lower section of said airbox to said transverse partition providing a plurality of conduits with alternate conduits thereof, connecting alternate tuyères with said transverse partition series of openings to said upper section and the remaining conduits connecting the balance of said tuyères with the lower section of said airbox.
